UNITED STATES PATENT OFFICE.

JUSTIN A. ELIAS, OF PHILADELPHIA, PENNSYLVANIA.

CARDBOARD CONTAINER.

Application filed April 4, 1927. Serial No. 180,766.

This invention, generally stated, relates to a container of flexible material and has more especial relation to a shipping box, barrel, carton, envelope or bag so constructed that the same may be folded to occupy a minimum amount of space and when required for use may be expeditiously set up in condition to receive articles or goods for shipment.

One object of the present invention may be said to reside in the provision of a cardboard or like container for shipping purposes in which the top and bottom of the container is provided with foldable leaves, opposed sets of leaves being provided with pintle accommodating members arranged to align one with another when the leaves are in closed position to accept a wire, cord or thread co-acting with the said members as a pintle.

Another object of the present invention is to provide a circular or oval shipping box, container or barrel made from a flat sheet of cardboard, sheet metal or other flexible material to which pintle receiving members are attached at two opposite edges so that when the sheet is folded to form a tube or barrel of circular or oval cross section the pintle receiving members mesh into alignment and form a longitudinal seam consisting of a row of holes through which a fastening pintle of wire, cord or thread is inserted.

Still another object of the present invention is to provide a mailing or shipping envelope or bag of paper, canvas or other material, which may have its two side members fastened around the edge by thread, wire or adhesives to form the envelope or bag but having one side or end open to receive the articles or material to be mailed, shipped or stored.

A further object of the present invention is to provide a shipping box, envelope, carton or bag of the character above stated in which the wire or the like forming the pintle is formed with a sealing medium after it is inserted in the pintle receiving members whereby tampering with the contents of the shipping box or carton is precluded without breaking of the seal.

Other and further objects of the present invention reside in the provision of general details of construction and arrangement and combination of parts for attaining the results sought by the foregoing objects.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in perspective of a shipping box or carton in sealed position and embodying features of the present invention.

Fig. 2, is a fragmentary view in perspective illustrating a pair of opposed leaves prior to a sealing operation.

Fig. 3, is a view in section taken upon the line 3—3 of Fig. 1; and

Fig. 4, is a detail view of the seal, although other forms of seals may be used.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1 designates a shipping box or container of flexible material as metal, pasteboard or the like and is provided top and bottom with opposed leaves 2 and 3. The container 1, as illustrated, is of rectangular structure. Each leaf 2 and 3 is provided upon its underside with a metallic strip 4 secured to the leaves 2 and 3 as by rivets 5. The metallic strips 4 riveted to the leaves provide an efficient reinforcement and the said reinforcing strips 4 are each provided with pintle receiving members 6, which pintle receiving members in the closed position of the leaves 2 and 3 are in alignment to receive a wire 7, as clearly shown in Fig. 1. The wire 7 or the like passes through the pintle receiving member 6 of all of the leaves 2 and 3 and around the periphery of the receptacle 1, as clearly shown in Fig. 1, and the free ends of the wire 7 or the like are securely locked to place by means of a seal 8. This seal 8 lies flat against one side of container 1, as clearly shown in Fig. 1.

In the case of a circular or oval container, a removable top and bottom of circular or oval shape and of suitable size to fit the container body can be inserted in or on the two

ends of the container body to form a complete closed container suitable for receiving materials or articles to be shipped or stored. To fasten the top and bottom pieces or lids 5 to the container body, glue or other adhesives could be used, but my invention includes the use of pintle receiving members attached to and suitably spaced to form a continuous row around the removable top 10 or bottom and near each end of the container body so that when the top or bottom is in place on the container body, the pintle receiving members are in alignment and a fastening pintle of wire or cord, can be threaded 15 through the row of pintle holes to retain the top or bottom in position.

In the case of an envelope or bag where the two edges of the envelope or bag form the receiving opening, a row of pintle receiving members is to be attached along each edge and spaced to bring the opposite pintle receiving members into alignment when the opening is closed, thus forming a continuous row of holes through which a fastening wire 20 or cord can be inserted. The envelope or bag can also be made with a top flap to cover the opening, in which case one row of pintle receiving members would be fastened to one side of the envelope or bag and the other to the lower edge of the hinged or removable 25 flap or cover so that the fastening wire can be inserted when the flap or cover is closed and the two rows of pintle receiving members are brought into alignment.

30 The above described rectangular shipping box or container as well as the circular box

and flat envelope or bag as previously described are very efficient for purposes desired in that it is impossible to tamper with the contents of the shipping box or container 40 without destroying the seal 8, thus providing a very acceptable medium for shipping by express or mail or for temporarily storing valuable articles.

It will now be apparent that I have devised 45 a novel and useful construction which embodies the features of advantage enumerated as desirable in the statement of the invention and the above description and while I have in the present instance shown and described 50 the preferred embodiment thereof which has been found in practice to give satisfactory and reliable results, it is to be understood that the same is susceptible of modification 55 in various particulars without departing from the spirit or scope of the invention or sacrificing any of its advantages.

What I claim is:

In a device of the character stated, a rectangular shaped shipping container of cardboard or the like having opposed foldable leaves top and bottom thereof, a flat metal strip having pintle receiving members fixed to each leaf, rivets for securing said strips to place, a wire passing through said pintle 60 receiving members and around said container, and a seal for securing the free ends of said wire together, the ends of said wire being embedded in said seal and said seal lying flat against one side of the container.

JUSTIN A. ELIAS.
